Attorney

UNITED STATES PATENT OFFICE.

ALBIN ANDERSON, OF ROCKFORD, ILLINOIS, ASSIGNOR OF ONE-HALF TO EMIL MOBERG,
OF ROCKFORD, ILLINOIS.

INTERNAL-COMBUSTION-ENGINE VALVE.

1,314,457.

Specification of Letters Patent. Patented Aug. 26, 1919.

Application filed May 10, 1918. Serial No. 233,694.

To all whom it may concern:

Be it known that I, ALBIN ANDERSON, a citizen of the United States, residing at Rockford, in the county of Winnebago and 5 State of Illinois, have invented certain new and useful Improvements in Internal-Combustion-Engine Valves, of which the following is a specification.

This invention relates to improvements in 10 internal combustion engines and it is the principal object of the invention to provide an engine having a novel form of valve means associated therewith whereby to cause the intaking and exhausting of the 15 fresh and spent gases to and from the cylinders of the engine; the construction of which is such as to reduce noise to minimum and to insure the proper functioning of the valve at all times, preventing the leakage 20 of gas or the loss of compression in the combustion chambers of the engine cylinders upon firing due to faulty valve seating.

Another and equally important object of 25 the invention is to provide a valve of the character mentioned having means for cooling the same during operation thus preventing overheating of the same, particularly by reason of the heated exhaust or spent gases which pass therethrough; a continuous 30 flow of cooling medium being maintained therethrough.

It is also an object of the invention to 35 provide the valve with means for lubricating the same when in operation and consequently permitting free movement thereof.

The foregoing together with additional 40 advantageous details and arrangement of parts of the preferred embodiment of my invention will be clear from the specific description hereinafter contained, when read in connection with the accompanying drawings forming a part thereof wherein said embodiment of the invention is illustrated for the purpose of facilitating a full understanding 45 of the said improvement.

In the drawings:

Figure 1 is a fragmentary vertical section through an internal combustion engine having my improved valves applied thereto, 50 Fig. 2 is a fragmentary horizontal section therethrough, and

Fig. 3 is a vertical section through one of the valves.

Having more particular reference to the 55 drawings, in connection with which like

reference characters will designate corresponding parts throughout the several views, 1 represents the cylinder of the engine and 2 the crank case thereof, said cylinder having valve receiving cylinders 3 60 and 4 arranged adjacent the same and communicating with the intake and exhaust ports 5 and 6 thereof, while pipes 7 and 8 communicate with suitable ports formed in said valve receiving casings, the valve 65 pipe 7 having connection with a suitable charge forming device while the pipe 8 discharges into the atmosphere.

Fixedly mounted on a portion of the crank shaft 9 which extends longitudinally 70 through the crank casing 2 and journaled in suitable bearings therein is a pinion 10 adapted to mesh with valve actuating gears hereinafter more fully described. For the purpose of illustration, I have shown in the 75 accompanying drawings but one cylinder of an internal combustion engine, it being understood, however, that the valve forming my invention may be used in connection with multiple cylinder engines and 80 when so applied is operated in the same manner hereinafter described. A piston 11 is slidably arranged in the engine cylinder 1 and is pivoted with a rod 12 having connection with one of the offset portions of 85 the crank shaft 9, while to ignite the explosive charge in the firing chamber of the cylinder I apply an ordinary type of spark plug 13.

Slidable in the cylinders 3 and 4 are the 90 improved valves, designated by the numerals 14 and 15, said valves being tubular and having ports 16 extending diametrically therethrough and adapted to be intermittently aligned with the ports in their respective cylinders. In this connection it will be noted that the exhaust valve 15 has the port 16 lined with asbestos or other suitable heat insulating material. Rods 17 are pivotally engaged with the tubular valves and extend 100 downwardly into engagement with certain of the offset portions of longitudinally disposed crank shafts 18 mounted in suitable bearings in the ends of the crank case and arranged substantially parallel with the 105 crank shaft 9. As will be noted, the inner surfaces of the tubular valves 14 and 15 are formed with longitudinally disposed ribs or fins 19, while a series of openings 20 are formed in the opposite sides thereof and 110

serve to permit the passage of lubricant directed on to the outer surfaces of the valves therethrough.

Engaged with the upper ends of the cylinders 3 and 4 are caps, the same having openings formed concentrically thereof which communicate with conduits 22 extending into engagement with the charge forming device of the engine whereby a suction 10 will be created in said cylinders. In this connection, it is to be noted that openings designated by the numeral 23 are formed in the casing of the engine at a point adjacent the crank case thereof and serve to permit 15 the inflow of air which is in turn drawn upwardly into the cylinders 3 and 4 by reason of the suction occurring therein.

It is to be noted that the engine is provided with the usual cooling medium circulating jacket whereby the temperature of the same will be maintained at the proper degree and hence, perfect functioning of the same is insured.

As means for imparting rotary motion to 25 the crank shafts 18 and to cause operation of the several valves 14 and 15 at predetermined intervals to effect the intaking and exhausting of the fresh and spent gases to and from the engine cylinder, gears 24 are 30 mounted on said crank shafts and mesh with another gear 25 mounted in suitable bearings on the edge of crank case and having connection with the pinion 10 carried by the crank shaft 9. As will be noted, the relative 35 size of the gear and the pinion is such as to cause the proper timing of the valves with their respective ports.

In operation, upon rotation of the crank 40 shaft 7 the piston 11 is moved in the cylinder to accomplish the usual intaking, compression, working and exhausting strokes, the several valves 14 and 15 operating in a manner to cause the alining of their respective ports with the ports of the cylinders 3 45 and 4 and the cylinder 1 at intervals to effect the intaking and exhausting of the fresh and spent gases to and from the same. By reason of the connection of the valves 14 and 15 with the crank shafts 18, the same 50 will be moved upwardly into alinement with

the ports 5 and 6 and upon continued rotation of said crank shaft will be immediately moved downwardly and disaligned therefrom, thus affording an exceedingly quick valve action which, as will be appreciated, is essential in multiple cylinder engines. By reason of the connection of the cylinders 3 and 4 with the charge forming device of the engine, a suction will be created therein and consequently a cooling draft of air will be at 60 all times maintained through the tubular valves 14 and 15, including the longitudinally disposed ribs or fins 19 and keeping them at the proper temperature. The valves are lubricated by the ordinary splash system, the crank shafts 18 thereof dipping into the lubricant and splashing a portion of the same on to the walls of the cylinders 3 and 4, which upon movement of the valves into engagement therewith will be evenly 70 applied over the same, the superfluous lubricant passing through the openings 20 and downwardly through the valves back into the crank case.

Manifestly, the construction shown is capable of considerable modification and such modification as is within the scope of my claims, I consider within the spirit of my invention.

I claim:

In combination with an internal combustion engine having intake and exhaust ports in the cylinder thereof, valve cylinders adjacent said engine cylinder and communicating therewith and having air inlet openings 85 adjacent their lower ends, open ended tubular valves slidable in the valve cylinders and adapted to intermittently establish communication between the valve and engine cylinders, longitudinally extending ribs formed 90 within said valves, and heads for the upper ends of said valve cylinders having air outlet openings formed therein whereby a conduit for communicating with a charge forming device may have communication with the 95 valve cylinders.

In testimony whereof, I affix my signature hereto.

ALBIN ANDERSON.
